UNITED STATES PATENT OFFICE.

JAMES S. CUMING, OF ST. LOUIS, MISSOURI.

PLURAL LAMP SOCKET.

Application filed February 21, 1921. Serial No. 446,837.

This invention relates to plural lamp sockets, such as may be used to attach more than one current consuming device to a single socket.

5 One of the objects of this invention is to provide a plural lamp socket which will be simple and cheap to construct, and durable and reliable in operation.

Another object of this invention is to provide a construction for such a lamp socket which shall provide a rigid frame connecting the conducting parts which may be easily assembled and connected.

15 Further objects will appear from the detail description taken in connection with the accompanying drawing, in which:

Figure 1 is a side elevation of a plural socket embodying this invention;

20 Figure 2 is a side elevation of the frame; Figure 3 is a section on the line 3—3, Figure 1;

Figure 4 is an inside view of one of the half parts of the body with the frame assembled; and

25 Figure 5 is an inside view of the other half part of the body.

Referring to the accompanying drawing, 1 designates a lamp socket conducting shell, such as may be procured on the market, with 20 an insulating closing cap 2 having a central contact assembled therewith. Two, or more of such shells may be assembled to form a frame work, such as shown in Figure 2. A conductor 3, which is preferably 25 a copper wire, is bent into a loop 4 near one end. A second conductor 5 also in the form of a wire is passed through the loop 4 and has its ends bent down as shown at 6. The two bent portions 6 and the end 7 of the conductor 3 are positioned so as to engage the central contacts of the shells 1. The conductors 3 and 5 are securely fastened together mechanically and electrically by soldering at their joint as shown at 8.

45 The shells 1 are arranged in angular relation to one another, the axis of one of them being coincident with or parallel to that of the conductor 3 and the axis of the others making preferably an angle 45° with said first axis. The shells are so positioned that the body of each of the side shells contacts directly with the central shell near its top at which point of contact the shells are securely connected mechanically and electrically by a soldered joint 9. The central shell extends beyond the side shells, thereby

permitting the latter to be placed closer together, and making the whole device compact and rigid. Each of the said side shells is further provided with a conductor 10 in 60 the form of a wire soldered or otherwise securely connected to the shell near its top and extending upwardly therefrom as shown in Figure 2 so as to be positioned to engage a plug shell as hereinafter described. 65

The body of this socket is composed of two half parts 11 and 12 of insulating material which are arranged to cover and enclose the frame work. One of these parts 11 is equipped with a threaded stem 13 adapted 70 to receive the threaded shell of a contact plug 14. The stem 13 is provided on one side with a shoulder 15 adapted to engage the other half part 12 which is cut off as shown at 16 for that purpose. 75

Each of the half parts 11 and 12 is provided with a set of chambers 17 corresponding in the two half parts so as to receive and enclose shells 1 of the frame. Each side chamber communicates with the central 80 chamber through a notch 18 adapted to permit contact between the shells in said chambers and to accommodate the soldered joint 9.

A channel 19 extends from each of said 85 side chambers upwardly toward the stem 13 and is adapted to accommodate one of the conductors 10. Said side chambers are each connected with the central chamber by a channel 20 adapted to accommodate the conductor 5 and having a depression 21 adapted 90 to accommodate the soldered joint 8. The channel 22 extends upwardly from the channel 20 toward the stem 13 and is adapted to accommodate the conductor 13. In the half 95 part 11, this channel connects with a duct 23 passing through the stem 13. The channels 19 are each provided with a notch 24 located just under the stem 13 and open to the outside of the body when the two halves are 100 assembled together.

In assembling this socket, the skeleton frame is constructed as shown in Figure 2. This is then placed in the half part 11 passing the conductor 3 through the duct 23 and laying the shells down into their respective chambers 17, and the conductors 3, 5 and 10 into their respective channels 22, 20 and 19. The stem 13 being provided with notches adapted to register with the notches 110 24, the ends of the conductors 10, when the frame is so assembled, may be placed in said

notches. The other half part 12 may then be assembled so as to cover and enclose the frame work and the two half parts may then be fastened together by means of bolts 5 25 passing through perforations 26 formed in both half parts for that purpose.

The plug shell 14 may now be screwed onto the threaded stem 13. When the plug 14 has been so assembled, the ends of the 10 conductors 10 will lie just beneath the shell thereof and the ends of the conductor 3 will protrude through the central opening in the central contact 27 thereof. Permanent connections may now be made by putting a drop 15 of solder at each of the points of contact of the conductors 10 with the shell 14 and at the end of the conductor 3 to connect it with the contact 27.

It will be seen that this invention 20 provides a rigid and durable structure for sockets of this kind. The rigid frame shown in Figure 2 is easily and cheaply constructed and is strong and durable. The connections of the conductors 5 and 3 to the central contacts of the sockets together with the soldered joint 9 directly connecting the bodies of the shells provide a construction which is very rigid and occupies a minimum of space. Again the connection of the conductors 10 25 and 3 with the plug 14 provides a rigid construction. The threaded stem engaging the plug 14 together with the rigid soldered connections of the conductors 10 with said plug form a safe and secure support for the socket 30 as a whole.

It is obvious that various changes may be made in the details of construction without departing from the spirit of this invention; it is, therefore, to be understood that this 40 invention is not to be limited to the specific details shown and described.

Having thus described the invention, what is claimed is:

1. A lamp socket comprising, a plurality 45 of contact shells, conductors connecting said shells, and an axially divided body having recesses to receive one of said shells and said conductors and having a stem received by

the other shell, said body having a notch adjacent the base of said last shell and the 50 conductor thereto adapted to permit connection of said parts from the outside.

2. A lamp socket, comprising, a plurality of contact shells, conductors connecting said shells, and an axially divided body having 55 recesses to receive one of said shells and said conductors, one of said body parts having a complete threaded stem enclosed by and occupying substantially the whole of the other shell and overlapping the other body part 60 at the base of said stem and said enclosing shell, said stem having a groove therealong to receive one of said conductors.

3. A lamp socket, comprising, a plurality of socket shells each having a central contact assembled therewith, said shells being 65 electrically connected together, a series of conductors connecting said central contacts, said connected shells and conductors providing an integral frame, an axially divided 70 insulating body made in two half-parts having corresponding chambers adapted to receive said frame, means on said body for receiving a plug shell to support the socket, means for connecting said plug shell with 75 said frame, and means for fastening said body parts together to enclose said frame.

4. A lamp socket, comprising a plurality of socket shells each having a central contact assembled therewith, said shells being 80 electrically connected together, a series of conductors connecting said central contacts, said connected shells and conductors providing an integral frame, an axially divided 85 insulating body made in two half-parts having corresponding chambers adapted to receive said frame, one of said parts having a threaded stem adapted to engage a threaded 90 plug shell to support the socket, means for connecting said plug shell with said frame, and means for fastening said body parts together to enclose said frame.

In testimony whereof I affix my signature this 1st day of November, 1920.

JAMES S. CUMING.
